(57) **CLAIM**

The ornamental design for a shoe upper with saddle, as shown and described.

DESCRIPTION

FIG. 1 is a perspective view of the shoe upper with saddle showing our new design;

FIG. 2 is a second perspective view thereof;

FIG. 3 is a right side elevational view thereof;

FIG. 4 is a left side elevational view thereof;

FIG. 5 is a front elevational view thereof; and,

FIG. 6 is a rear elevational view thereof.

The semi-oval portion in FIGS. 1, 3, and 5 is merely indicating potential logo. The different amount of shading on the saddle pieces are intended to show separate pieces and do not represent any particular color or colors.
